UNITED STATES PATENT OFFICE.

WILLIAM C. SEERS AND FREDERICK W. NEW, OF LOS ANGELES, CALIFORNIA.

DAVIT STRUCTURE.

1,289,933.

Specification of Letters Patent. Patented Dec. 31, 1918.

Application filed April 16, 1918. Serial No. 228,966.

To all whom it may concern:

Be it known that we, WILLIAM C. SEERS, a subject of the King of Great Britain, and FREDERICK W. NEW, a citizen of the United

5 States, both residing at Los Angeles, in the county of Los Angeles and State of California, have invented new and useful Improvements in Davit Structures, of which the following is a specification.

10 This invention relates to a davit for hoisting and lowering objects over the side of a vessel and is especially adapted for use with life boats, nets and the like.

15 It is an object of this invention to provide a structure by which the objects to be lowered may quickly be swung from the deck of the vessel and over the side thereof, and whereby it may be maintained, while being lowered, some distance from the side of the 20 boat to prevent injury by the object swinging and striking against the side of the vessel.

25 It is another object to provide a davit structure, which will permit a life boat to be filled on the deck of the vessel with passengers, and then swung over the side thereof and lowered to the water.

30 In addition to the broader features of design, other objects of this invention are to provide details of structure, whereby simplicity and durability of construction as well as ease and certainty of operation are secured.

35 We attain these objects by means of the embodiment of our invention illustrated in the accompanying drawing, in which:

40 Figure 1 is a side elevation of a fragment of a vessel having our improved davit construction mounted thereon, the davit construction being shown in closed position.

45 Fig. 2 is a side elevation of the construction shown in Fig. 1. Fig. 3 is a plan view of a mechanism for operating the davit structure. Fig. 4 is a side elevation showing the 50 davit structure open and in its first position for lowering a boat. Fig. 5 is a side elevation showing the davit structure in the second position in lowering a boat. Fig. 6 shows the last position of the davit structure. Fig. 7 is a plan view of the davit structure in the position shown in Fig. 6.

55 Referring more particularly to the drawing, a fragment of the side of a vessel is indicated conventionally by 9. Pivoted secured to the side of the vessel are brackets

10 and 11. Mounted upon the top of brackets 10 and 11 adjacent the free ends thereof is a tilting cradle 12. Suspended from the cradle 12 is a life boat 13.

60 The brackets 10 and 11 are secured to the side of the vessel by tubular bearings 14 and 15. As these bearings are duplicates of each other only one will be described, namely, 14. The tubular member 14 is slit longitudinally throughout its length as indicated by 65 Notches 17, 18 and 19 are formed therein and communicate with the slit 16. The notches are beveled for a purpose later described. Slidably and pivotally mounted within the tubular member 14 is a post 20. 70 The bracket 10 has fingers 21, 22, and 23, which are disposed in the notches 17, 18 and 19 respectively and are secured to the post 20. It is evident that when the structure is 75 in the position shown in Fig. 1 the brackets 10 and 11 may be swung outwardly through 90 degrees into the open position shown in Figs. 4 to 7 inclusive. When the brackets are in their open position, they may be moved to slide axially of the tubular members 14 80 and 15; the fingers 21, 22 and 23 slide in the slit 16. The post 20 is made of such length with respect to the length of the tubular member 14 that the bracket 10 may move downwardly in the latter. When the fingers 85 21, 22 and 23 are out of registration with the notches 17, 18 and 19, the bracket is held in open position.

Rotatably mounted upon the end of brackets 10 and 11 are supports 24 and 25. 90 Mounted in the supports 24 and 25 is a shaft 26 upon which the cradle 12 is journaled. The cradle 12 comprises end members 27 and 28 joined at the top by a cross member 29. The cradle 12 is journaled upon the 95 shaft 26 at the lower ends of the cross members 27 and 28. Joined to the end members 27 and 28 adjacent the shaft 26 are rearwardly extending members 30 and 31, which are disposed at right angles to the aforesaid 100 end members. A member 32 joins members 30 and 31. Members 30, 31 and 32 form a tilting extension, which serves as a support for the cradle when in upright position and as a lever to tilt the cradle when the boat 105 is to be lowered.

Various means may be used to operate the davit construction just described, and we have shown herein a mechanism for operating the same, but as this forms no part of 110

our invention, we do not limit ourselves thereto. The mechanism shown is merely for illustrative purposes.

The top of post 20 is formed with teeth 5 on its periphery as indicated by 33 in Fig. 3. The teeth do not extend entirely around the post, but form in effect a mutilated gear. The post in tubular member 15 is of the same construction. Mounted upon the deck 10 of the vessel is a spur gear 34 meshing with the teeth 33. Secured to the spur gear 34 is a bevel gear 35. Meshing with bevel gear 35 is a bevel pinion 36, which is fixed to a shaft 37 mounted in bearings on the 15 deck of the vessel. The shaft 37 is operated by a motor 38. A similar set of gearing is operated from the shaft to move the post in tubular member 15. Upon operation of the motor 38, the shaft 37 will be rotated, there- 20 by turning the posts in the tubular members 14 and 15 until the brackets 10 and 11 have been swung outwardly. After the brackets have reached a position at right angles to the side of the boat, the teeth 25 on the end of the post will have been moved so that they no longer mesh with their respective spur gears, and the shaft 37 can continue to rotate without interference. When the brackets 10 and 11 are in open 30 position they may slide downwardly in the tubular members 14 and 15. They are however held in their upper position by means of cables 39 and 40.

As the cables are duplicates, only one will 35 be described. Cable 40 is led over a sheave 41, and the free end thereof is secured to the top of the post in tubular member 15. Cables 39 and 40 are wound upon drums 42 and 43, which are fixed to a shaft 44. Rotatably mounted upon shaft 44 is a spur gear 45 provided with a clutch member. Spur gear 45 meshes with a pinion 46 fixed to shaft 37. Splined upon shaft 44 is a clutch member 47 adapted to clutch the gear 45 40 to the shaft 44. A suitable lever and linkage indicated by 48 is arranged to operate the clutch member 47. Fixed to shaft 44 is a brake drum 49, which is operated by a lever in the stand of levers 50. It is ob- 50 vious that after the brackets have been swung into open position, the drums 42 and 43 may be allowed to rotate, thereby lowering the brackets by means of the cables 39 and 40. The clutch drum 49 with its corresponding levers controls the movement of shaft 44 when it is free from the gearing.

In mesh with the gear 45 is a gear 51. Splined to the shaft 52, to which gear 51 is fixed, is a clutch member 53 adapted to 55 engage a corresponding clutch member secured to drum 54. Drum 54 is rotatably mounted upon shaft 52. A brake drum 55 is fixed to the drum 54 for controlling the same, and is operated by an appropriate lever in the stand 50. Wound upon drum

54 is a cable 56, the free end thereof being connected to the cross piece 29 on the cradle. This drum and cable are operated to pull the cradle into upright position. A shaft 57 is geared to gear 51 by gearing 58. Splined 70 upon shaft 57 is a clutch member 59, adapted to engage a corresponding clutch member secured to the drum 60. Drum 60 is journaled upon the shaft 57 and is provided with a brake drum 61, which is controlled 75 by appropriate linkage connected to a lever in the stand 50. Wound upon the drum 60 is a cable 62, which is secured to the cross piece 32 on the tilting portion of the cradle.

After the brackets 10 and 11 have been 80 swung into open position as shown in Fig. 4, the drums 42 and 43 are operated to permit the brackets to move into their lower position as shown in Fig. 5. The drum 60 is then operated to wind cable 62 thereon and 85 thereby tilt the cradle into position shown in Fig. 5. The cable 56 is permitted to unwind from the drum 54, thereby permitting the cradle to swing into its open position shown in Fig. 6. In this position the life boat 13 90 may be released.

To hoist the life boat the drum 54 is operated to wind cable 56 thereon and bring the cradle into upright position. The drums 95 42 and 43 are next operated to raise the brackets into the position shown in Fig. 4. The motor 38 is now reversed, thereby swinging the brackets against the side of the vessel. The fingers on the brackets readily slide into the notches on the tubular 100 members due to the beveled edges of the latter. The davit construction is now in the position shown in Fig. 2, and again ready for operation.

If there are a number of decks upon the 105 vessel, the tubular members 14 and 15 may be made long enough, so that after the brackets are swung outwardly the boat may be lowered to the level of any deck and then filled with passengers by using a gang plank or other suitable means for reaching the boat from the deck.

To securely hold the brackets in their open 110 position cables 63 and 64 may be employed, these being attached to the side of the cradle and fastened to suitable hooks upon the side of the vessel as shown in Fig. 7.

What we claim is:

1. In a davit construction, the combination of brackets secured to a vessel for swinging outwardly, and a cradle adapted to support a boat mounted upon said brackets for tilting outwardly. 120
2. In a davit construction, the combination of brackets secured to a vessel for swinging outwardly, and a cradle adapted to support a boat mounted upon said brackets for tilting outwardly, said cradle having tilting extension. 125
3. In a davit construction, the combina- 130

tion of brackets, means securing said brackets to a vessel for swinging outwardly and for sliding movement toward and from the water, and a cradle adapted to support a 5 boat mounted upon said brackets for tilting outwardly.

4. In a davit construction, the combination of brackets, means securing said brackets to a vessel for swinging outwardly and 10 for sliding movement toward and from the water, and a cradle adapted to support a boat mounted upon said brackets for tilting outwardly, said cradle having a tilting extension.
- 15 5. In a davit construction, the combination of brackets, tubular supporting members secured to a vessel, said tubular members being slit longitudinally and provided with notches, posts journaled in said tubular 20 member, said brackets being secured to said

posts by fingers adapted to register with said notches when the brackets are in their upper position, and a cradle adapted to support a boat mounted upon said brackets for tilting outwardly.

- 25 6. In a davit construction, the combination of brackets, tubular supporting members secured to a vessel, said tubular members being slit longitudinally and provided with notches, posts journaled in said tubular member, said brackets being secured to said 30 posts by fingers adapted to register with said notches when the brackets are in their upper position, and a cradle adapted to support a boat mounted upon said brackets for 35 tilting outwardly, said cradle having a tilting extension.
